(57) CLAIM

The ornamental design for a handle bracket, as shown and described.

DESCRIPTION

FIG. 1 is a front elevation view of a handle bracket showing my new design.

FIG. 2 is a left side elevation view thereof. The right side is a mirror image of FIG. 2.

FIG. 3 is a top plan view thereof.

FIG. 4 is a bottom plan view thereof; and,

FIG. 5 is a rear elevation view thereof.

Features shown in phantom lines are to illustrate the environment only.

1 Claim, 2 Drawing Sheets

FIG. 1

FIG. 2

FIG. 5

FIG. 3

FIG. 4
